AUTOMATIC DRAWBAR AND CAR COUPLER

Lloyd Price, Van Wert, Ohio, and Leroy Price,
Muncie, Ind.

Application August 17, 1937, Serial No. 159,584

1 Claim. (Cl. 213—116)

Our present invention pertains to improved automatic draw-bar and car coupler and it contemplates the provision of means so constructed and arranged that it permits the knuckle of the coupler to open sufficiently wide so as to comply with Federal laws with regard to coupler construction.

The invention further contemplates the provision in a lock-bar and car coupler whereby the knuckle arrangement serves as a base to permit the coupling pin to be held in such a position so that the knuckle can open to its full width without the pin dropping and locking the knuckle in an open position.

The invention further contemplates the provision in a car-coupler of an extension whereby when the knuckle is closed the extension rests behind a retaining wall and in event of the knuckle pin breaking, the shank of the knuckle 20 would remain in position and permit pull of the cars and this arrangement guarantees positive operative working of the knuckle and coupler regardless of the accidental displacement of the usual knuckle pin.

The invention further contemplates the provision in a knuckle coupler of a retaining wall in which the spring present in all couplers is "built in" and this construction in addition to strengthening the body portion of the coupler serves as 20 a base against which the knuckle rides when closed, thereby forcing it to stay in said closed position should the knuckle pin break.

The invention further contemplates the provision of a closed spring housing arranged in the 35 coupler by use of an iron spring plug and mounted so as to protect the spring from exposure to weather conditions thereby eliminating an objection generally present in couplers now in use.

The invention further contemplates a coupler 40 having built up bumper portions on the top and bottom thereof whereby the body portion of the coupler adjacent the lock-bar is materially strengthened and in addition the bottom outside edges of the jaws are arranged with flanges 45 which also tend to strengthen the body head of the coupler.

Other objects and advantages will be fully understood when read in connection with the drawings and specification attached hereto, in which 50 Figure 1 is a plan view of my novel coupler construction.

Figure 2 is a side elevation thereof.

Figure 3 is a horizontal section taken in the plane 3—3 in Figure 2 and looking in the direction of the arrows, and further illustrating the

knuckle before coupling and in normal position.

Figure 4 is a view similar to Figure 3 but showing the device after coupling with particular attention invited to the dual locked position of my novel extension with the usual pin.

Figure 5 is a transverse sectional view taken in the plane indicated by 5—5 of Figure 3 and showing the pin in its uncoupled position.

Figure 6 is a similar view to Figure 5 and taken in a plane indicated by the line 6—6 of Figure 4 and showing the pin down as when adjacent cars are coupled.

Figure 7 illustrates in sectional view the action that takes place should one or both of the pins of the knuckle be lost and further illustrating 15 how the extension holds behind and abuts the spring casing so as to prevent displacement of the jaws with respect to each other.

Figure 8 is a detailed view of the construction of the inner end of the knuckles and showing the arrangement of the stud that constantly holds the spring with regard to the jaws or knuckles notwithstanding the direction of movement of said jaws.

Figure 9 is a detailed view showing the locking bar and the depending pin thereof.

Similar numerals of reference designate corresponding parts in all the views of the drawings.

Our novel device comprises the usual coupler shank 1 indicated as a whole having the head indicated as a whole by 2 and the ears 3 and adapted to pass through the ears are pintles 4 while also adapted to be engaged by the pintles 4 is a knuckle or jaw 5 that in turn is provided with a nose 6 and a body portion or arm 1. Particular attention is directed to the fact that formed integral on the inner ends or rear arms of each of the knuckles or jaws 5 is the extension or nose 8 and this nose 8 is one of the salient features of my invention and because of the construction of the interior wall of the head 2 and the spring retaining casing the nose or extension 8 will always travel and be confined within the interior of the head 2 during the closed or operative position of the coupler. This extension is however, permitted to ride to such a position when the jaws are opened that said jaws will be opened sufficiently to comply with Federal requirements.

Adapted to enter the head 2 is a locking bar 9 having a depending pin 10 and the said pin is 40 adapted to enter a slot in the head 2 and regardless of whether the pin 4 is lost or broken the spring and extension will retain the depending pin 10 in its seat so that operation of the locking bar will be precluded when the jaws are closed.

A clevis 11 is secured by means of a pintle 12 to the bar 9 and a chain 13 is secured to the clevis and permits operation of the locking bar.

Formed in and mounted on the head 2 is an abutment or spring housing that extends slightly beyond the lateral edge of the head and depends within the head and is in fact an integral portion of said head. This abutment materially increases the tensile strength of the head and is

- 10 provided with the bore 15 that in turn confines the jaw actuating spring 16. The normal action of this spring and the confinement hereof within the bore 15 is controlled by the plug 17 and mounted on the inner edge of the body portion 7 15 of the nose 6 and adjacent and in close proximity to the extension 8 is a stud 18. This stud 18 engages the spring on its inner end and guides said spring during the operation of the jaws. The spring tends to bias the knuckles to an open 20 position and the abutment 14 as before stated acts in conjunction with the inner under wall of the head constituting a chamber or confining space for the extension during the locked position of the jaws or knuckles regardless of existing conditions and the said extension in conjunction with the pin 10 of the bar 9 permits pulling of cars regardless of the loss or breakage of one or both of the pintles 4 or coupled abutting jaws. The device is simple in construction, inex-

pensive to produce and is a safe guard against injury to train crews when coupling or uncoupling cars.

What we claim is:

A coupler comprising a shank, a head formed integral on the shank, a spring housing formed in one piece in the head and having a lower portion extending within said head, the rear wall of said lower portion and the under wall of the head constituting the walls of a chamber, said head having a nose formed on one end thereof, a knuckle having a rear arm pivotally arranged on the head and actuatable in one direction by means of a draw bar, a spring confined within the spring housing, a stud mounted on the rear 15 arm of the knuckle and adapted to engage the spring to bias the knuckle to an open position, an integral extension formed on the rear arm of the knuckle and so constructed and arranged that it is normally confined within said chamber 20 when the knuckle is in the locking position whereby casual displacement or breakage of the pin by which the knuckle is hinged on the head will prevent the extension from being unseated within its confined space, substantially as and 25 for the purpose specified.
